UNITED STATES PATENT OFFICE.

WILLIS A. WEAVER, OF DETROIT, MICHIGAN.

SANDWICH-VENDING MACHINE.

Application filed November 20, 1922. Serial No. 602,226.

To all whom it may concern:

Be it known that I, WILLIS A. WEAVER, a citizen of the United States, and resident of Detroit, in the county of Wayne and State of Michigan, have invented a new and useful Improvement in Sandwich-Vending Machines, of which the following is a specification.

This invention relates to sandwich vending devices adapted to be installed in public and other convenient places for dispensing sandwich lunch packages and other desirable articles for which the device may be adapted and employed.

The object of my invention is to provide a simple and practically useful device that is conveniently accessible at all times for the purpose of supplying persons desiring sanitary, economic, quick and light ready lunch service.

A further object is to provide a coin controlled device whereby a coin of the required denomination must first be dropped in the machine in order to complete the successful operation of the mechanism thereof; and also, a package discharged into the pocket receptacle of the delivery door of the cabinet, which automatically unlocks same for its removal. This mode of construction renders the machine closed, automatically locked and unlocked, and more completely sanitary by obviating any susceptibility of the interior of the cabinet or any of the packages contained therein to the collection of, or contact with dust, or contamination with other particles of unsanitary matter.

These objects and purposes I attain by the device illustrated in the accompanying drawings, in which Figure 1 represents a front view of the exterior of the cabinet; Figure 2 is an enlarged sectional view of Fig. 1, on line 2 2, looking to the left, showing in part the incased mechanism employed to operate the device; Figure 3 is a transverse cross sectional view on line 3 3, Fig. 2, looking down, showing the front and rear metal angle plates which form the rectangular hollow shape of the package receptacle, with the lower ends of their front panels bent and inclined forward, and also a side sectional view of the swinging-plate 6, which controls the opening and closing of the outlet for packages passing through the receptacle channel at this point; Figure 4 is a detail view of Fig. 2, in section on line

4 4, looking to the right, showing a cross sectional view of the coin channel member 17, and the sliding plunger 12, engaged in the plunger guide 17^A, thereof; Figure 5, 60 is an exterior front view of the cabinet 1, provided with a glass C in the front panel thereof, rendering visible packages in the interior package receptacle; and also a glass D in the front panel of the delivery door 5, rendering the visibility of packages when deposited into the pocket receptacle on the interior side thereof; Figure 6 is a sectional view of Fig. 5, on line 6 6, showing in perspective the interior compartment of 70 the package delivery door 5, and also the swinging or oscillating latch attachment 24, employed for automatically locking said door; Figure 7 is a broken transverse view 75 of the front panel of cabinet 1, on line 7 7, Fig. 6, showing a plan view of the interior side of the package delivery door 5, and also the automatic oscillating swing locking attachment 24, with their upper arm extensions 24', pivotally attached at 24^A, 80 to the interior side of the front panel of cabinet 1, one on each side of, and directly above the door casing of said door 5, and provided with guide plates 25, attached to the interior side of the front panel of the 85 cabinet, for holding the latch plates 24 in line when they swing outward or inward, and with the lower integral free arm extensions 24'' curved so as to slightly extend, 90 one on each side of, and into the pocket receptacle of the delivery door 5; Figure 8 is a detail view in perspective of the package delivery door 6, showing the interior pocket construction thereon formed by the side flanges 5', and with the bottom flange 95 bent upward forming the rear panel 5''; also the slots 27 in the upper portion of the side flanges 5'; and Figure 9 illustrates the rear package supply door 21 in a side view, 100 inclined and partly open with dotted positions of packages as they appear arranged in the holder or receptacle 3, attached to the interior side thereof.

Referring to the drawings, similar numerals and letters of reference refer to 105 similar parts throughout the several views.

The cabinet 1, provided with a delivery door 5, for the removal of purchased packages, hinged or pivoted, preferably at the bottom of the door casing in the front 110 panel of the cabinet so as to swing and open outward; a slot 10'' for the movement of

an operating lever 10; a depositing coin slot 17' registering with the perpendicular receptive end 17^B, of the coin channel member 17 of the interior mechanism of the device; a package supply door 3, forming the upper back panel of cabinet 1; and a coin door 18, which forms the lower back panel of the cabinet and employed for the purpose of removing coins deposited in the cabinet, and also for the adjustment and regulation of the interior mechanism therein, constitute the exterior cabinet and frame work of the device, and shown in Figs. 1, 2, 5 and 9.

15 The interior mechanism and construction of the device inclosed in cabinet 1, consists of a package receptacle formed by the two semi-rectangular shape metal plates 2 and 3; the former being attached to the interior 20 upper side of the front panel of the cabinet 1, by means of brackets 2'', while the latter is similarly attached by brackets 3' to the opposite interior side of the supply door panel 21, with the lower front panel ends 25 of both similarly flared or bent forward in parallel inclines 2' and 3', respectively, and which extend upward from the bottom, also from the turn-plate 6, a little more than the thickness of a package contained in the 30 receptacle, as indicated in Fig. 2.

It will be seen that the arrangement of the two semi-rectangular shaped metal plates 2, 3, in this manner, with their channel chambers facing and contiguous to each 35 other, form a repository and receptacle for the packages or articles vended by the machine. And for controlling and discharging articles from the outlet at the bottom or lower end of this package receptacle, a 40 turn-plate 6, is pivotally attached to the side flanges of the rear channel plate 3, slightly back of the incline projection 3', thereof, and which is provided with rear arm extensions E, terminating in a forward upper curve engaging the slot-openings 6', provided for same in the incline projecting flange 3' of the rear channel plate 3. These arm extensions E, are adapt- 45 ed to move forward through the slot open- 50 ings 6' under the package directly above the one supported on pivotal plate 6, when said plate is turned downward to the inclined dotted position indicated in Fig. 1, and which causes a package thereon to slide off 55 through the channel of a metal guide 4, into the receptacle of the delivery door 5, thus permitting the swing-plate 6 to be returned to its horizontal closed position 60 by means of a spiral coiled spring 7, attached to one of the arm extensions E and the interior side of the rear panel of the cabinet, as shown in Fig. 2.

65 The coin channel member 17, with which the machine is provided, is attached, preferably, to one of the interior side panels of

the cabinet, with its perpendicular forward end opening, 17^B, registering with the coin slot opening, 17', in the front panel of the cabinet, and extends back in a slightly downward inclined plane approximately to 70 the center of the cabinet, where it terminates in an upper perpendicular guide, 17^A, for the sliding plunger 12, and in which it is free to move.

The horse-shoe magnet 16, controlling a 75 slot opening 16' provided in the rear end of the coin channel member 17, and employed for the removal of slugs that may be dropped in the machine, is integrally at- 80 tached to the lever arm 15, which is pivot- 85 ally attached to the interior side of the cabinet at 15', the short arm of which is pivotally connected to the operating lever 10, by means of a short connecting rod 14.

Lever 9, pivotally attached at one end to 85 the interior side of the front panel of the cabinet at 9', the movement of which is controlled by a connecting-rod 8, pivotally attached to it and to the drop-plate 6, is employed and arranged so that the free end 90 thereof will control the slot opening 9'' at the lower bottom end of the coin channel member directly under the plunger 12, and which is provided for the outlet of coins deposited in the machine for the purchase 95 of a package, and through which coins are forced under the pressure of and contact with the sliding plunger 12, in its downward movement, as indicated by dotted po- 100 sitions in Fig. 2.

To render the sanitary condition of the cabinet more complete, the delivery door 5, is provided and placed in the front panel of the cabinet with the flange extensions as 105 indicated in Fig. 8, which over-lap and contact closely the front panel casing of the exterior cabinet, as shown in Figs. 1 and 5, and in section in Figs. 2, and 6. This arrangement obviates the tendency of dust or other particles of contaminating matter collecting 110 in the interior pocket receptacle of the delivery door 5, or the interior of the machine from the outside.

The delivery door 5, is also shown in Figs. 6 and 7, provided with two swing-latches 24, having their upper arm extensions 24' pivot- 115 ally attached to the interior side of the front panel of the cabinet 1, one each side of, and over the door casing at 24^A, and with their free arm-extensions 24'' curved so as to extend inside of the door pocket and flanges 5', which form the sides thereof, and in contacting position with packages dis- 120 charged from the drop-plate 6, through the guide channel 4, into the pocket receptacle of 125 said door 5, and which in their movement contact with and force the said swinging latch plates 24 to swing outward a sufficient distance to disengage them from the slot open- 130 ings 27 in the side flanges 5' of the delivery

door 5, thus permitting the same to be opened and the package removed from the pocket thereof, and when the door is released, by freeing the hold of the knob or handle 5''' thereon, it automatically closes by means of the spiral coiled spring 5''' attached to the flange 5' of said door 5, and to one of the panel sides of the guide channel 4, the base of which is attached to the 10 interior side of the front panel of the cabinet 1, and with the perpendicular upper end terminating in a flared incline rearward, so that the swinging end of the drop plate 6, will contact therewith at its extreme open 15 position, similarly as indicated in dotted position in Fig. 2.

The metal guide plates 25, with recessed flange extension bent at right-angle to the base thereof, and in which the latch-plates 24 are free to move, are attached to the interior side of the front panel of the cabinet, are employed for the purpose of obviating any lateral motion of said plates and to retain them in proper and positive positions of 25 alignment with the slots 27 when the delivery door 5 is closed; and the beveled edge 26 of the latches 24 enable said latches to move outward more easily when contacting with the flange sides 5' on the return of 30 said door to its normal closed position, illustrated in Figs. 1, 2, 5, 6 and 7.

In Figure 1 is shown a view of the exterior of the cabinet 1, in which the packages vended are invisible, while in Fig. 5 shows 35 the cabinet provided with a glass C in the front panel thereof which renders some of the packages contained in the supply receptacle or holder, visible, and also a glass D in the panel of the delivery door 5, to render 40 a package visible when dropped into the pocket receptacle thereof. Either of these methods may be employed without affecting the operation of the device or the spirit of my invention.

In the operation of my device, the supply receptacle is first filled with packages of uniform size, and preferably, one upon and above the other, similarly as illustrated in Fig. 5, and also in dotted position in Figs. 45 2 and 9. The lower bottom package in the perpendicular supply channel, by virtue of its own weight, and which is augmented by the weight of the packages above it, will move down and forward into the incline 50 channel chamber at the base of said supply receptacle and rest on the drop-plate 6, and in which position it becomes partly relieved of the weight of the packages above, which becomes checked by the next lower package 55 resting on the incline projection 3', similarly as indicated in Fig. 2.

And when a coin of the required denomination is inserted in slot 17', it will drop into the receptive end 17^b, of the coin channel member 17, and roll to the rear end there-

of, directly under the sliding plunger 12, and into the slot 9'', and rest on the free end of the lever 9, controlling the opening and closing of said slot; and with a part of its periphery contacting with the magnet 16 in the slot opening 16', as indicated in dotted position in Fig. 2; then by pressing the key A, of the operating lever 10 down a full stroke, the sliding plunger 12 which is operated by a short connecting link 11 70 pivotally attached to it and also to the operating lever 10 will move down upon said coin and force it through the slot opening 9'' and thereby moving the free end of the lever 9 down and open to a position indicated in Fig. 2, where the coin becomes released and drops to the bottom of the cabinet. 75

Thus it is apparent that any opening or closing movement of the lever 9, will likewise cause a similar and simultaneous movement of the swing-plate 6, as both are pivotally connected by rod 8, shown in Fig. 2; and also by the downward and open movement of drop plate 6, a package thereon 80 will be discharged through the guide channel 4, into the pocket receptacle of the delivery door 5, and in this movement of package transference, the said package contacts with the free ends 24'' of the swing latch plates 24, moving them back and from 85 disengagement in the slots 27, thus, unlocking 90 and permitting the delivery door 5 to be opened and the package removed from 95 the pocket thereof.

The magnet 16 is employed to reduce the loss of packages in case where metal slugs are dropped into the machine for the purpose of defrauding same; and especially when said slugs are made of such metals as may be affected and attracted by a magnet. In my device the polar ends of a horse-shoe magnet 16, close and control the opening slot 16' for the removal of slugs in the coin channel member 17, and which 100 swings outward and upward to the dotted position indicated in Fig. 2 when the operating lever 10 is pressed down, and by means of the pivotal lever 15 integral therewith being pivotally connected to the said operating lever 10 by the short lever 14, the said magnet 16 will simultaneously move 105 outward drawing any metal slug affected thereby through the slot opening 16', whence it then drops to the bottom of the cabinet 1, without operating the delivery and drop plate 6, or causing a package to be discharged or delivered. 110

Having thus described my invention, what I claim is:—

1. In a coin controlled mechanism, a coin channel member having bottom and end outlets, and also provided with a plunger guide above the bottom outlet; a plunger mounted in said plunger guide, an operating lever connected to said plunger, a second 125

lever operatively connected to the said first lever, a magnet carried by the said second lever and normally located at the end opening, and a member below said bottom opening adapted to operate a vending machine.

2. In a coin controlled mechanism, a coin channel member having bottom and end outlets, and also provided with a plunger guide above the bottom outlet; a plunger mounted in said guide, an operating lever connected to said plunger, a second lever operatively connected to the first lever, a magnet carried by the second lever and normally located at the end opening.
3. In a device of the character described, the combination comprising a coin channel member having bottom and end outlets, and also provided with a plunger guide above the bottom outlet, a plunger mounted in said plunger guide, an operating lever connected to said plunger, a spring connected to said

lever for retaining it in normal position, a second lever operatively connected to the first lever, and a magnet carried by said second lever and normally located at the end outlet.

4. The combination in a device of the character described, consisting of a coin channel member having bottom and end outlets, and also provided with a plunger guide above the bottom opening; a plunger mounted in said plunger guide, an operating lever connected to said plunger, a spring connected to said lever for retaining it in normal position, a second lever operatively connected to the first lever, and a magnet carried by said second lever and normally located at the end outlet, and a member below said bottom opening adapted to operate a vending machine.

WILLIS A. WEAVER.
